US00D965627S

(12) **United States Design Patent** (10) Patent No.: **US D965,627 S**
Liebowitz et al. (45) Date of Patent: **** Oct. 4, 2022**

(54) **DISPLAY SCREEN OR PORTION THEREOF WITH GRAPHICAL USER INTERFACE FOR MANAGING DIABETES**

(71) Applicant: **Embecta Corp.**, Andover, MA (US)

(72) Inventors: **Edward Liebowitz**, Jersey City, NJ (US); **Linda Sloan**, Springfield, VA (US); **Meghan Nichols**, Leesburg, VA (US)

(73) Assignee: **Embecta Corp.**, Andover, MA (US)

(**) Term: **15 Years**

(21) Appl. No.: **29/808,970**

(22) Filed: **Sep. 24, 2021**

Related U.S. Application Data

(60) Continuation of application No. 29/744,444, filed on Jul. 29, 2020, now Pat. No. Des. 933,099, which is a division of application No. 29/614,006, filed on Aug. 15, 2017, now Pat. No. Des. 908,134.
